RECLAMATION OF USED SYNTHETIC LUBRICATING OILS

Alfred H. Matuszak, Westfield; James W. Hand, Jr., Green Village, and John C. Munday, Cranford, N. J., assignors to Esso Research and Engineering Company, a corporation of Delaware

Application October 27, 1954, Serial No. 465,118

4 Claims. (Cl. 260—485)

This invention relates to a method for recovering valuable components of complex esters from oil compositions containing such complex esters and more particularly relates to a method for recovering the dibasic acid and glycol components of complex esters from synthetic lubricating oil compositions containing such complex esters.

In an effort to obtain superior lubricating oils having specific and unusual characteristics, new synthetic lubricants have been developed. One class of material which has attracted unusual interest as synthetic lubricants are those materials which are known to the art as the complex esters. In general these synthetic lubricating oils are characterized by higher viscosity indices and lower pour points than mineral oils of corresponding viscosity. Lubricants possessing such properties have special value in the lubrication of engines which are subjected to high temperatures such as combustion turbine engines, particularly those of the "prop-jet" type. Mineral oil lubricants are generally less desirable for use in such engines because of their tendency to result in a higher percentage of carbonaceous residue which accumulates on moving parts and interferes with the operation of the engine. In addition, the relatively high pour points and low flash points of such compositions are undesirable. The synthetic lubricants of the complex ester type are especially adaptable to use under such conditions since these lubricants have a desirable combination of high flash points, low pour points, and high viscosities, and eliminate or reduce, in a great number of applications, the necessity for additive agents. Generally these complex esters which are utilized in synthetic lubricant blends for jet aircraft have the following ranges of properties:

ASTM flash point	420°—550° F.
ASTM pour point	Below —65° F.
Kinematic vis./210° F.	9 to 11 cs.
Kinematic vis./—40° F.	11,000 to 25,000

In addition to the complex esters, commercially useful synthetic lubricants preferably contain diesters of dibasic acids and monohydric alcohols. It has been found that a synthetic lubricating oil base stock containing both complex esters and diesters is superior in many respects to the individual stocks. Also, commercial synthetic lubricants may contain small amounts of additives such as tricresyl phosphate, phenothiazine, sulfonates, lecithin, sorbitan monooleate, and the like.

After synthetic lubricants have been used for some time in jet aircraft and the like, they become unacceptable for further use due to the presence of contaminants such as water, low boiling hydrocarbons, acids, metals, metal salts, sludge, carbonaceous solids, and the like. Heretofore such used synthetic lubricants have been processed to recover their diester content by distillation and the remainder of the synthetic lubricant, including the complex ester, has been discarded. Thus the expensive components of the complex esters, such as the glycol component and particularly the costly dibasic acid component,

2

have not been recovered heretofore. Due to the non-volatile nature of the complex ester, the distillation process employed to recover the volatile diester has not been feasible in commercial distillation units. In addition to the complex esters which are discarded in used synthetic lubricants, there is also on occasion a substantial amount of the complex esters discarded as a result of off-specification batches of synthetic lubricants. Thus it is apparent that it would be highly desirable to have a process available which could be utilized to recover the valuable components of complex esters, particularly the expensive glycol and dibasic acid components, so as to thereby eliminate the discard of such costly materials.

A novel method has now been found for recovering the glycol and dibasic acid components of complex esters from oil compositions, such as used or off-specification commercial synthetic lubricating oil compositions. The new method involves the transesterification of the complex ester by a reaction between the complex ester and a monohydric alcohol whereby the dibasic acid component is converted to a diester and the glycol component is converted to free glycol. In general, the method of this invention comprises heating a mixture comprising the oil composition which contains the complex ester, a monohydric alcohol, and an esterification catalyst until at least a portion of the complex ester is transesterified into a free glycol product and a diester product and subsequently removing at least one of the products from the mixture. The method of this invention may be utilized to recover such components from any complex ester containing at least one dibasic acid residue and at least one glycol residue. More specifically, the method of the present invention may be utilized to recover the glycol and dibasic acid components from a complex ester having the following general formula:

where A is selected from the group consisting of monobasic acid residues and monohydric alcohol-dibasic acid residues, B is selected from the group consisting of monohydric alcohol residues and monobasic acid-glycol residues, and x is an integer of about 1 to 6. It will be understood that where the complex esters are set forth in this specification in the form of a formula of the type shown above that it is implied that the various components (alcohols, glycols and acids) are joined together with the elimination of water as occurs in an esterification reaction. Such formulae are utilized in this specification to simplify the description of the complex esters.

The method of this invention, wherein a complex ester is reacted with a monohydric alcohol in the presence of an esterification catalyst, may be illustrated by the following equations involving a particular complex ester:

The desired overall reaction is shown by the following equation:

In general, it is preferred to utilize a sufficient amount of alcohol to obtain substantially complete transesterification of the complex ester. Preferably an amount of alcohol in excess of that stoichiometrically required to con-

vert all of the dibasic acid components to diesters is utilized in order to assure substantial completion of the transesterification reaction. It will be understood that the method of this invention is applicable to complex esters other than the particular type shown in the above equations.

Generally, synthetic lubricant compositions will contain a combination of a complex ester and a diester. The method of this invention may be utilized to recover complex ester components from such compositions or other oil compositions containing as little as about 1% by volume of complex ester. In general, if the oil composition contains less than about 10% by volume of the complex ester, it is preferred to initially remove the original diester by distillation prior to carrying out the transesterification reaction with the complex ester. When the proportion of complex ester is greater than about 10% by volume, the original diester may be similarly removed by distillation prior to the transesterification reaction, although it is generally preferred to carry out the transesterification reaction of the complex ester first and then to separate the original diester along with the newly formed diester from the resultant reaction mixture. It has been found that higher recoveries are obtained by carrying out the transesterification reaction of the complex ester in the presence of the original diester in such instances. Preferably the monohydric alcohol utilized in the transesterification reaction corresponds to the monohydric alcohol residue of the original diester contained in the synthetic lubricating oil compositions since this simplifies the recovery of the diesters. The glycol recovered by the method of this invention may be utilized, for example, in the preparation of new complex esters which may then be used to prepare new synthetic lubricating oil compositions. The diester formed in the transesterification reaction may be used, for example, as the diester component of new synthetic lubricating oils, as a plasticizer, etc. The method of this invention may be carried out by a batch or continuous procedure.

As has been stated, the method of this invention may be utilized to recover the glycol and dibasic acid components of any complex ester containing at least one glycol residue or radical and at least one dibasic acid residue or radical. Generally, the complex esters which are utilized commercially in synthetic lubricant compositions and which may be reclaimed in the method of this invention have the following general formula:

where A is selected from the group consisting of monobasic acid residues and monohydric alcohol-dibasic acid residues, B is selected from the group consisting of monohydric alcohol residues and monobasic acid-glycol residues, and x is an integer of about 1 to 6. In general, the complex esters utilized in synthetic lubricating oils are predominantly those where x equals 1, although during the preparation of such complex esters, higher molecular weight esters, such as those where x is in the range of about 2 to 6, are also formed in lesser proportions. Also, during the preparation of these complex esters, a certain amount of diesters will normally be formed. Thus, the overall product resulting from the preparation of complex esters will generally be a mixture of diesters and complex esters of varying molecular weight.

The following five types of complex esters may be utilized in the method of this invention and thus their glycol and dibasic acid residues may be recovered as a free glycol product and as a diester product, respectively:

TYPE I.—MONOBASIC ACID - GLYCOL - DIBASIC ACID-GLYCOL-MONOBASIC ACID

This complex ester may be represented by the following structural formula:

wherein R_1 and R_5 are the alkyl radicals of the monobasic

acids, R_2 and R_4 are the alkyl radicals from the glycols, and R_3 is the alkyl radical from the dibasic acid.

The esters of this type may be prepared by admixing the calculated amounts of the various compounds and carrying out a straightforward esterification reaction. The reaction conditions are continued with an occasional sample of the product being tested for acidity until the minimum acidity is attained.

10 TYPE II.—ALCOHOL-DIBASIC ACID-GLYCOL-DIBASIC ACID-ALCOHOL

This material may be represented by the following formula:

wherein R_1 and R_5 are the combining radicals of the alcohol, R_2 and R_4 are the alkyl radicals of the dibasic acid, and R_3 is the alkyl radical of the glycol.

These esters are prepared in the manner similar to those of Type I.

TYPE III.—ALCOHOL-DIBASIC ACID-GLYCOL-MONOBASIC ACID

These esters are prepared by reacting a dibasic acid and a glycol under such conditions that one hydroxyl group of the glycol combines with one carboxyl group of the dibasic acid; in other words, a half ester is formed. This half ester is then reacted with a molar proportion each of an aliphatic alcohol and a monobasic acid. These materials may be said to have the general formula:

wherein R_1 is the combining radical of the aliphatic alcohol, R_2 the alkyl radical of the dibasic acid, R_3 the alkyl radical of the glycol, and R_4 the alkyl radical of the monobasic acid.

The preparation of these ester materials is specifically set out in U. S. Patent No. 2,575,195.

40 TYPE IV.—ALCOHOL-DIBASIC ACID-GLYCOL-DIBASIC ACID ALCOHOL

These materials may be said to have the general formula:

wherein R_1 and R_5 are the combining alkyl radicals of the alcohol, R_2 and R_4 the alkyl radicals of the dibasic acid, and R_3 is the alkyl radical of the glycol.

It will be noted that the esters of Type IV have the same structural formula as Type II. However, these complex esters are prepared by reacting an alcohol with a dibasic acid under such conditions that a half ester is formed and reacting two moles of such an ester with one mole of a glycol. The preparation of this type of synthetic ester lubricating oil is set out in detail in copending application Serial No. 52,429, now issued as U. S. Patent 2,703,811.

TYPE V.—MONOBASIC ACID-GLYCOL-DIBASIC ACID-GLYCOL-MONOBASIC ACID

These synthetic esters may be said to have the general formula:

wherein R_1 and R_5 are the alkyl radicals of the monobasic acid, R_2 and R_4 are the alkyl radicals of the glycol, and R_3 is the alkyl radical of the dibasic acid.

It will be noted that these synthetic esters are the same as those appearing above under Type I except that this type is prepared by reacting a monobasic acid with a glycol under such conditions that a half ester is formed and reacting two moles of such ester with one mole of a dibasic acid. The details of the preparation of this type of synthetic ester are set out in U. S. Patent No. 2,575,196.

As was set out above, these complex ester materials are prepared by a combination of an alcohol, a mono-

basic acid, a dibasic acid, and a glycol in various fashions.

Preferably the alcohols used to prepare the complex esters have 5 to 10 carbon atoms per molecule. However, other alcohols may be used if desired.

Operable alcohols used to prepare the complex esters include the following alkanols:

Amyl alcohols
2-ethylbutyl alcohol
n-Hexyl alcohol
n-Octyl alcohol
2-ethylhexyl alcohol
Nonyl alcohol
Decyl alcohol
C₇, C₈, C₉, C₁₀, C₁₃ Oxo alcohols

The commonly known ether alcohols formed by the reaction of ethylene oxide or propylene oxide with aliphatic alcohols and known in the industry as "Dowanol," "Carbitols," or "Cellosolves," may also be used.

A group of alcohols especially adapted for use in preparing complex esters are the so-called "Oxo" alcohols, prepared by the reaction of carbon monoxide and hydrogen upon the olefins obtainable from petroleum products. Materials such as diisobutylene, C₇ olefins such as propylene-butylene copolymer, and C₉ and C₁₂ olefins such as tri-propylene and tetra-propylene are suitable for this purpose; also higher and lower molecular weight olefinic materials are sometimes employed. The alcohols obtained in this manner normally have a branched chain structure.

The monobasic acids are those preferably having about 4 to 13 carbon atoms per molecule. However, other monobasic acids may be employed if desired. Among the monobasic acids which may be employed to prepare complex esters, the following alkanoic acids may be listed as illustrative:

Propionic acid
Butyric acid
2-ethylbutyric acid
Valeric acid
Caproic acid
2-ethylhexoic acid
Caprylic acid
C₈ Oxo acids
C₁₀ Oxo acids
Lauric acid
C₁₃ Oxo acids
Any of the corresponding "thio" acids

The dibasic acids are those preferably having about 4 to 10 carbon atoms per molecule. However, other dibasic acids may be employed, if desired. Illustrative example of the dibasic acids which may be employed in the synthesis of the complex esters are the following alkanedioic acids.

Succinic acid
Adipic acid
Pimelic acid
Suberic acid
Azelaic acid
Sebatic acid
Isosebatic acid
Trimethyl adipic acid
α Methyl adipic acid

The glycols employed in preparing complex esters include ethylene glycol and any of the paraffinic homologues of the same containing up to 18 carbon atoms. These may include, for example, saturated glycols such as ethylene glycol, propylene glycol, butylene glycols, trimethylene glycol, tetramethylene glycol, pentamethylene glycol, and the like. Since the glycols may also contain oxygen or sulfur atoms, compounds such as di-

ethylene glycol, triethylene glycol, the polyethylene glycols of the formula:

5 where *n* is 1 to 26 and the polypropylene glycols of the general formula:

10 where either R₁ or R₂ is a methyl group and the other is hydrogen, and where *n* is 1 to 20, preferably 2 to 6, may likewise be employed. Glycols containing sulfur atoms in thioether linkages may also be employed, and these include compounds as thiodiglycol and 1,2-bis(2-

15 hydroxy-ethylmercapto) ethane. There also may be used glycols containing both oxygen and sulfur in similar linkages; such a compound is bis-2(2-hydroxyethoxy) ethyl sulfide.

When the complex esters described above are to be utilized as lubricants for jet aircraft, the reactants, i. e., the acids, alcohols and glycols, will be selected and reacted together to form complex esters having the properties (flash point, pour point, viscosity) set forth in detail heretofore. Generally, such complex esters will contain in the range of about 20 to 130 carbon atoms per complex ester molecule.

It will be understood that the oil compositions from which the glycol and dibasic acid complex ester components may be recovered in accordance with the method of this invention may contain other materials such as, for example, mineral lubricating oil base stocks. Also, used oil compositions may contain water and hydrocarbon contaminants such as kerosene, naphtha, light gas oils and the like. The compositions may also include diesters such as those of the dibasic acids and monohydric alcohols described above. These diesters may actually represent in the range of about 0 to 99% by volume of the total lubricating oil composition. Also, the oil compositions may contain various conventional additives such as tricresyl phosphate, phenothiazine, sulfonates, lecithin, sorbitan monooleate, pentaerythritol monooleate, polyacrylates and polymethacrylates.

The method of this invention comprises heating a mixture comprising (1) an oil composition containing the complex ester, (2) a monohydric alcohol, and (3) an esterification catalyst until at least a portion of the complex ester is transesterified into a free glycol product and a diester product and subsequently removing at least one of the products from the mixture. The monohydric alcohols which may be utilized in the transesterification reaction are preferably those set forth heretofore as being useful for forming the complex esters. The alcohol used in the transesterification reaction may be the same as that used originally in the preparation of the complex ester (when the complex ester contains a monohydric alcohol residue). The alcohol which is utilized in the transesterification reaction may also be the same as that used originally in the preparation of the diester base stock (when the oil composition contains such diester components). 50 Quite generally, it will be found that synthetic lubricant compositions will contain both complex esters and diesters prepared from the same alcohol. Thus, particularly in the recovery of complex ester components from such compositions, it is preferred to utilize the same alcohol 55 in the transesterification reaction as was utilized in the preparation of the original base stock mixture of diester and complex ester. This facilitates the recovery by narrowing the range of diester volatilities.

It is preferred to use in the transesterification reaction 70 an amount of monohydric alcohol which will be sufficient to react with all of the dibasic acid components of the complex ester to form diesters as well as to react with any monobasic acid components to form simple esters. Generally, it is preferred to utilize an amount of alcohol in excess of the stoichiometric amount in order to assure

a more rapid and complete transesterification reaction. In general, therefore, it is desirable to use at least about 2 moles of monohydric alcohol per dibasic acid unit and 1 mole of monohydric alcohol per monobasic acid unit in each mole of the complex ester. Amounts in excess of this, as much as 8 moles or more per dibasic acid residue, may be utilized if desired. With complex esters which are alcohol stoppered, that is complex esters which have alcohol residues at the extremities of the molecule, it is preferred in general to use at least 2 moles of alcohol per dibasic acid unit in each complex ester molecule. Any excess alcohol remaining upon completion of the transesterification reaction may be recovered by distillation from the reaction mixture and utilized for further transesterification reactions.

The esterification catalyst utilized in the method of this invention may be any conventional esterification catalyst. Such catalysts are well known to the art and include the following:

Sulfuric acid
Sodium hydrogen sulfate
p-Toluene sulfonic acid
Sulfosalicylic acid

The amount of catalyst utilized in the reaction is preferably about 0.1 to 1% by weight, based on the total reactor charge.

The reaction is carried out at an elevated temperature such as a temperature in the range of about 70° to 300° C.; preferably a temperature in the range of about 150° to 250° C. is employed. The reaction is carried out for a period of time sufficient to convert at least a portion of the complex ester into a free glycol product and a diester product. Preferably the reaction is carried out until substantially all of the complex ester has been transesterified into the diester product and glycol product. The reaction time required to accomplish this will depend upon the batch size and will generally be in the range of about 0.5 to 10 hours and preferably in the range of about 2 to 6 hours. In general, the method of this invention may be utilized to recover complex ester components from oil compositions containing in the range of about 1% to about 100% by volume of complex esters.

The glycol and diester products formed in the transesterification reaction as well as any diester originally present in the original oil composition are preferably separated from the remainder of the composition by distillation at a reduced pressure in the range of about 0.01 to 10.0 mm. Hg, preferably about 0.2 to 1.0 mm. Hg, to thereby avoid thermal degradation of these materials.

The method of this invention will be more fully understood by reference to the single figure drawing which is a diagrammatic illustration of apparatus adapted to carry out the method of the present invention. In this drawing, reference character 10 designates a storage tank containing a used synthetic lubricating oil composition containing at least about 1% by volume of a complex ester such as di-2-ethylhexanol-sebacic acid-tetraethylene glycol-sebacic acid-di-2-ethylhexanol. The remainder of the synthetic lubricating oil base stock comprises a diester such as di-2-ethylhexyl sebacate or C₈ Oxo azelate. Valves 11 and 12 in conduits 13 and 14, respectively, are then opened to pass the used synthetic lubricating oil composition into distillation tower 20 which may be any conventional distillation tower adapted to remove water and low boiling hydrocarbons such as kerosene, gas oils, naphtha, and the like, overhead. The water and low boiling hydrocarbon impurities are removed overhead from tower 20 through conduit 21. Also if the original oil composition contained mineral lubricating oil base stocks, these oils will also be removed overhead from tower 20.

The remainder of the used synthetic lubricating oil composition is removed as a bottoms fraction from tower

20 through conduit 22 and is passed through conduits 23, 24, 25, and 26 into reactor 40. A monohydric alcohol, such as 2-ethylhexanol, is introduced into reactor 40 from storage tank 41 by opening valve 42 in conduit 43. The monohydric alcohol enters reactor 40 through conduits 43 and 44. Then an esterification catalyst, such as NaHSO₄, is introduced into reactor 40 from hopper 45 by opening valve 46 in conduit 47. The proportions of reactants in reactor 40 are selected as described in detail heretofore. The reaction mixture comprising the used synthetic lubricating oil, the monohydric alcohol and the esterification catalyst is heated to an elevated temperature in reactor 40 by means of an electric heating coil or a heating coil 39 through which a heating medium, such as steam, Dow-Therm, mercury and the like, is introduced and removed, respectively, through conduits 38 and 37. The reaction mixture in reactor 40 is preferably thoroughly mixed by means such as by mixer 48 operated by motor 49. Any low boiling materials not removed overhead in tower 20 which are volatilized in reactor 40 may be removed from reactor 40 through vent line 50. The resultant transesterification reaction is carried out in reactor 40 at the conditions described in detail heretofore.

After the transesterification reaction has progressed to the desired point, the entire contents of reactor 40 are passed to filter 52 through conduit 53 by opening valve 54. Filter 52 removes from the reaction mixture any solid material, such as catalyst, carbonaceous solids, and the like and may be a filter press, a blotter press, an Oliver filter, a bed of clay or the like.

The filtered reaction products are thereafter passed through conduits 55, 56, and 57 into distillation tower 70 by opening valve 58 in conduit 56. Tower 70 is any conventional distillation tower adapted to take overhead through conduits 71 and 72 any unreacted monohydric alcohol in the reaction mixture. Valve 73 is opened to permit this monohydric alcohol to be removed overhead through conduits 71 and 72 through which the unreacted monohydric alcohol may be passed to storage. The remainder of the reaction mixture is then passed from the bottom of tower 70 through conduit 74 into distillation tower 80 which may be any conventional distillation tower adapted to take overhead a glycol through conduit 81. Thus in tower 80 the glycol formed in the transesterification reaction carried out in reactor 40 is separated as a substantially pure product from the reaction mixture.

The remainder of the reaction products is then withdrawn from the bottom of tower 80 through conduits 82 and 84 and is passed into distillation tower 90 which is any conventional distillation tower equipped to take a diester product, such as di-2-ethylhexyl sebacate, overhead through conduit 91. Thus the overhead product of distillation tower 90 includes any original diester base stock present in the synthetic lubricating oil composition contained in tank 10 as well as the diester product formed in reactor 40 by the transesterification of the complex ester. Any complex ester which has not been transesterified into glycol and diester components may be withdrawn from the bottom of tower 90 through conduits 92 and 93 by opening valve 96. It will thus be seen that the synthetic lubricating oil contained in tank 10 has been separated into a glycol component removed overhead from tower 80 and a diester component removed overhead through tower 90; also any unreacted alcohol remaining after the transesterification reaction in reactor 40 has been recovered as an overhead stream from tower 70.

Rather than originally removing any water and low boiling hydrocarbon contaminants and/or mineral lubricating oil base stocks from the used synthetic lubricating oil in tower 20, if desired these relatively low boiling materials may be removed after the transesterification reaction. This is accomplished by opening valves 11

and 15 in conduits 13 and 16, respectively, and closing valve 12 in conduit 14 so that the used synthetic lubricating oil in tank 10 may be passed through conduits 13, 16, 23, 24, and 25 directly to reactor 40. Thereafter, when the transesterification reaction has been completed, the filtered product from filter 52 may be passed through conduits 55 and 61 by opening valve 62 in conduit 61 and closing valve 58 in line 56 such that the filtered products are introduced into distillation tower 60. Tower 60 is any distillation tower adapted to take water and volatile hydrocarbons overhead through conduit 63. In this manner, it will be seen that the low boiling hydrocarbon contaminants and/or mineral lubricating oil base stocks may be removed after the transesterification reaction is completed. The reaction mixture may then be passed from the bottom of tower 60 successively to towers 70, 80, and 90 for further separation therefrom of alcohol, glycol and diester, respectively.

Also, if desired, the used synthetic lubricating oil passing through line 23 from tower 20 may be passed to distillation tower 30 through conduits 31 and 32 by closing valve 26 in conduit 24 and opening valve 33 in conduit 31. Distillation tower 30 may be any conventional distillation unit adapted to take overhead through conduit 34 any original diester base stock contained in the used synthetic lubricating oil. The remainder of the used synthetic lubricating oil composition may then be passed from the bottom of tower 30 through conduits 35, 25, and 26 to reactor 40. This particular method of operation is especially desirable when the used synthetic lubricating oil composition originally contains less than about 10% by volume of complex ester. In this manner, the feed stock to reactor 40 may be concentrated so that it contains a high proportion of the complex ester, thereby simplifying the transesterification reaction. This particular method of operation is also useful when the original diester base stock contained in the used synthetic lubricating oil composition is not the same diester as that formed in reactor 40 in the transesterification reaction and subsequently removed overhead from distillation tower 90 through overhead conduit 91. In this way, therefore, it is possible to separately recover the two different diesters. When distillation tower 30 is employed, it is preferable to also utilize distillation tower 20 to remove low boiling contaminants such as water and hydrocarbons. In this way, the diester product taken overhead through overhead conduit 34 through tower 30 is not contaminated with such low boiling materials. When operating in this manner, the filtered reaction products from filter 52 are by-passed around distillation tower 60 since the low boiling contaminants have previously been removed in distillation tower 20.

The method of this invention is readily adapted to a continuous process. For example, the following is a description of a preferred method of operation wherein it is desired to remove the original diester base stock from the used synthetic lubricating oil prior to the transesterification reaction. Used synthetic lubricating oil is continuously withdrawn from tank 10 and continuously passed to distillation unit 20 through conduits 13 and 14. Low boiling contaminants are continuously removed overhead from tower 20 through overhead conduit 21. The remainder of the used synthetic lubricating oil is continuously passed from the bottom of tower 20 through conduits 22, 23, 31, and 32 into tower 30. The original diester base stock is continuously removed overhead from tower 30 through overhead conduit 34 and the remainder of the used synthetic lubricating oil base stock is continuously passed from the bottom of tower 30 through conduits 35, 25, and 26 into reactor 40.

A large volume of reaction mixture is maintained in reactor 40 and the portion of the used synthetic lubricating oil passing through conduit 26 into reactor 40, as well as the catalyst continuously flowing from hopper 45 and alcohol flowing through conduit 44, is introduced at such

a rate into reactor 40 that the residence time thereof in reactor 40 will be sufficient to obtain the desired degree of transesterification. A portion of the reaction mixture in reactor 40 is continuously withdrawn therefrom through conduit 53 and is continuously filtered through filter 52. The filtered reaction products are thereafter passed through conduits 55, 56, and 57 into distillation tower 70 from which unreacted alcohol is taken overhead through conduit 71. In this continuous method of operation, it is preferred to recycle the separated unreacted alcohol through conduits 71, 75, and 44 back to reactor 40. This is accomplished by closing valve 73 in line 72 and opening valve 76 in conduit 75. Make-up alcohol is supplied to reactor 40 from tank 41 through conduit 42 wherein it is mixed with the separated alcohol in conduit 44.

The reaction products from the bottom of tower 70 are passed continuously from the bottom thereof through conduit 74 to distillation tower 80 where glycol formed in the transesterification reaction is continuously taken overhead through overhead conduit 81. The bottoms from distillation tower 80, which contain the diester formed in the transesterification reaction, may be continuously passed through conduits 82, 85, and 32 back to distillation tower 30. This may be accomplished by closing valve 83 in conduit 84 and opening valve 86 in conduit 85. In this manner, it will be seen that the original diester base stock, together with the diester formed in the transesterification reaction, is removed continuously overhead through overhead conduit 34 of tower 30 and any unreacted complex ester is recycled back to reactor 40.

As an alternative, the bottoms from tower 80 may be continuously passed through conduits 82 and 84 into distillation tower 90 where the diester formed by transesterification is removed overhead continuously through overhead conduit 91. This is accomplished by closing valve 86 in conduit 85 and opening valve 83 in conduit 84. The bottoms from tower 90 may be continuously discarded from the system by passing them through conduits 92 and 93 by opening valve 96 in conduit 93. As an alternative, the bottoms from tower 90 may be passed through conduits 92, 94, and 26 back to reactor 40. This may be accomplished by closing valve 96 in conduit 93 and opening valve 95 in conduit 94. In this manner, the bottoms from tower 90 which may contain a substantial proportion of complex ester may be recycled back to reactor 40 for transesterification. Preferably, in this method of operation, a minor portion of the bottoms from tower 90 are continuously or intermittently discarded from the system through conduit 93 so as to purge the system of any high boiling liquid contaminants.

In cases where the used synthetic lubricating oil contains more than about 10% by volume of complex ester, it is preferable to carry out the transesterification reaction in the presence of the diester base stock contained in the original used synthetic oil composition. This method may be carried out continuously as follows: Used synthetic oil from tank 10 may be continuously passed through conduits 13 and 14 to distillation tower 20 to remove therefrom low boiling contaminants. The bottoms from tower 20 may then be continuously passed through conduits 22, 23, 24, 25, and 26 into reactor 40. Esterification catalyst and monohydric alcohol are continuously passed into reactor 40 through conduits 47 and 44, respectively, and the reaction product and the transesterification reaction in reactor 40 are continuously removed therefrom. The rate of introduction of reactants and catalyst is adjusted such that their residence time in reactor 40 is sufficient to give the desired degree of transesterification.

The reaction products from reactor 40 are continuously passed through conduit 53 to filter 52 and the filtered reaction products are passed continuously through conduits 55, 56, and 57 to tower 70. The unreacted alcohol removed overhead from tower 70 is continuously recycled to reactor 40 and free make-up alcohol is passed to reactor 40 from tank 41. The bottoms from tower 70 are passed

continuously to tower 80 from which glycol is continuously removed overhead through overhead conduit 81. The bottoms from tower 80 are then passed from conduits 82 and 84 into tower 90 where the diesters, including both the original diester base stock and the diesters formed in the transesterification reaction, are continuously removed overhead through conduit 91. The bottoms from tower 90 may be discarded from the system through conduits 92 and 93 or, if desired, they may be recycled back to reactor 40 through conduits 92, 94, and 26. The recovered diester may contain trace amounts of contaminants such as phenothiazine, high boiling glycols, tricresyl phosphate, rust inhibitors, etc. It may be used as is or the contaminants may be removed by suitable processing such as alkali washing, charcoal or alumina treatment. The resulting diesters are useful as synthetic lubricant bases, chemical intermediates, or as plasticizers. By reacting the recovered diester with recovered glycol, complex esters suitable for use as blending agents may be prepared.

It will be apparent that the method of this invention will suggest other modifications to those skilled in the art and it will be understood that such modifications may be made without departing from the spirit of the present invention.

The invention will be more fully understood by reference to the following example. It is pointed out, however, that the example is given for the purpose of illustration only and is not to be construed as limiting the scope of the present invention in any way.

Example

A used synthetic lubricating oil composition which had previously been used in actual flight service of a turbo-prop aircraft engine was employed in this example. The original synthetic lubricating oil composition had the following formulation:

ORIGINAL SYNTHETIC LUBRICATING OIL COMPOSITION

Ingredient:	Wt. percent
Synthetic oil base stock ¹	99.0
Phenothiazine	1.0
	100.0

¹ Base stock prepared by blending about 25% by volume of di-2-ethylhexyl sebacate with about 75% by volume of a complex ester reaction product consisting of about $\frac{1}{3}$ by weight of di-2-ethylhexyl sebacate and about $\frac{2}{3}$ by weight of a complex ester of the approximate formula: 2-ethylhexanol-sebacic acid (tetraethylene glycol-sebacic acid) C_5 -2-ethylhexanol. The complex reaction product was obtained by reacting about 2.4 moles of 2-ethylhexanol with about 1 mole of glycol and about 2 moles of sebacic acid under esterification conditions.

Valuable components of this used synthetic lubricating oil composition were reclaimed by five different methods as follows.

Method I.—To 250 g. of the used synthetic lubricating oil was added 250 g. of 2-ethylhexanol and 1.25 g. of NaHSO_4 catalyst. The mixture was refluxed with stirring at 195° C. for 4 hours to convert the complex esters to di-2-ethylhexyl sebacate. The mixture was filtered which thereby removed the catalyst, then stripped free of unreacted alcohol at reduced pressure before finally removing glycol and the original and newly-formed diester. The distillation was carried out to a final liquid temperature of 280° C. The lower boiling contaminants, such as water and low boiling hydrocarbons, alcohol, and glycol were removed at a temperature below about 200° C. vapor temperature at a pressure of 0.5 mm. Hg. The diesters were removed at a temperature in the range of about 200° C. to 235° C. vapor temperature at a pressure of about 0.5 mm. Hg.

Method II.—To 250 g. of the used synthetic lubricating oil was added 250 g. of 2-ethylhexanol. No NaHSO_4 was added as a catalyst. This mixture was processed in an identical manner to the mixture of Method I.

Method III.—To 250 g. of the used synthetic lubricat-

ing oil composition was added 1.25 g. of NaHSO_4 . No 2-ethylhexanol was added. This mixture was processed in an identical manner to the mixture of Method I.

Method IV.—In this method, 250 g. of the used synthetic lubricating oil composition were processed by the procedure set forth in Method I except in the absence of 2-ethylhexanol and in the absence of NaHSO_4 catalyst.

Method V.—In this method, 126 g. of the bottoms of Method II were blended with 250 g. of 2-ethylhexanol and 1.25 g. of NaHSO_4 . This mixture was then processed in a manner identical to that described in Method I.

The following results were obtained by the above-described five different methods:

Table I.—Conversion of used synthetic oil to recoverable diester

Method	Weight of Forerun (gms.) ¹	Weight of Diester (gms.) ²	Weight of Bottom (gms.)	Diester Yield (Percent)
I	230	228	40	91.2
II	265	104	128	41.6
III	13	105	132	42.0
IV	14	104	132	41.6
V	231	101	40	³ 40.4(80.2)

¹ Includes water, low boiling hydrocarbons, glycol, and alcohol removed by distillation (<200° C. @ 0.5 mm. Hg).

² Diester removed by distillation (200-235° C. @ 0.5 mm. Hg). Includes original diester base stock plus diester formed by transesterification.

³ 80.2% yield based on 126 gms. of starting material.

It will be noted that substantial increases in the yields of diester were obtained only in the case of the catalyzed 2-ethylhexanol reactions (Method I and Method V) which were carried out in accordance with the method of the present invention. Without catalyst and/or without alcohol (Methods II, III, and IV) the normal diester yield was about 42%, but with the combination of catalyst and alcohol the diester yields were approximately doubled. With this type of used synthetic lubricating oil, which normally contains about 50 to 55% of complex esters, conversion in the presence of the original diester (Method I) gives a better yield than when the original diester is first removed (Method V). It is believed that diester solvency may be a factor contributing to this difference.

What is claimed is:

1. A method for preparing a glycol and diester from a complex ester having the formula:

$A-(\text{glycol-alkanedioc acid})_x-\text{B}$

wherein A is selected from the group consisting of alkanoic acid residues and alkanol-alkanedioc acid residues, B is selected from the group consisting of alkanol residues and alkanoic-glycol residues, all of said glycols being saturated, and x is an integer of about 1 to 6, said method comprising mixing said complex ester with a C_5 to C_{10} alkanol capable of replacing the glycol from said complex ester and an esterification catalyst, heating said mixture to an elevated temperature until a portion of said complex ester is esterified into a free glycol product and a diester product of said alkanedioc acid, removing said catalyst, then separating said products from said mixture by distillation.

2. A method according to claim 1 wherein said mixture initially also contains a diester of said alkanol and said alkanedioc acid.

3. A method for recovering a glycol and diester from a complex ester having the general formula:

Alkanol-alkanedioc acid-(glycol-alkanedioc acid)_x-alkanol

wherein said alkanol is a C_5 to C_{10} alkanol, said alkanedioc acid is a C_4 to C_{10} dicarboxylic acid, said glycol is saturated and x is 1 to 6, said complex ester having lubricating oil qualities and containing a total of 20 to 130 carbon atoms, said method comprising mixing said

13

complex ester with a C_5 to C_{10} alkanol and an esterification catalyst, heating said mixture to an elevated temperature until a portion of said complex ester is esterified into a free glycol product and a diester product of said alkanedioic acid, removing said catalyst from said reaction mixture, then separating said products from said mixture by distillation.

4. A method for recovering glycol and diester from a synthetic lubricating oil composition wherein the synthetic oil base stock consists essentially of (A) a diester having the formula:

Alkanol-alkanedioic acid-alkanol

and (B) a complex ester having the formula:

Alkanol-alkanedioic acid-(glycol-
alkanedioic acid)_x-alkanol

wherein said alkanol is a C_5 to C_{10} alkanol, said alkanedioic acid is a C_4 to C_{10} dicarboxylic acid, said glycol is saturated, and x is 1 to 6, said complex ester having

14

5 lubricating oil qualities and containing a total of 20 to 130 carbon atoms, said method comprising mixing said lubricating oil composition with a C_5 to C_{10} alkanol and an esterification catalyst, heating said mixture to an elevated temperature until a portion of said complex ester is esterified into a free glycol product and a diester product of said alkanedioic acid, removing said catalyst from said reaction mixture, then separating said products from said mixture by distillation.
